BY

UNITED STATES PATENT OFFICE.

JOHN J. KEARNEY, OF BERWYN, AND GEORGE H. WINTER, OF CHICAGO, ILLINOIS.

DESIGN FOR A STATUETTE.

56,100.

Specification for Design.

Patented Aug. 17, 1920.

Application filed January 6, 1920. Serial No. 349,817. Term of patent 3½ years.

To all whom it may concern:

Be it known that we, JOHN J. KEARNEY and GEORGE H. WINTER, citizens of the United States, residing at Berwyn and Chicago, resp., in the county of Cook and State of Illinois, have invented a new, original, and ornamental Design for a Statuette, of which the following is a specification, reference being had to the accompanying drawing, forming part thereof.

We claim:

The ornamental design for a statuette, as shown.

JOHN J. KEARNEY.
GEORGE H. WINTER.
